HIGHWAY TRAFFIC SIGNAL

William C. Nein and Thomas W. Varley, New
York, N. Y.

Application May 31, 1929, Serial No. 367,397

1 Claim. (Cl. 177—339)

This invention relates to the control of traffic signals on highways where the main highway signals are normally indicating for clear traffic continuously, and the cross street signals are normally indicating for stop continuously.

To allow for cross street traffic to take place, a vehicle on a cross street when approaching a main highway causes the traffic signals to reverse and indicate clear for the cross street and stop for the main highway. After the vehicle has passed away from its position of control, the traffic signals return to normal. Timing devices may be used so that a second vehicle wishing to pass over the main highway, will not cause a signal change until some definite time has elapsed since a previous change.

The object of the invention is to provide apparatus such that the desired objects may be obtained when the control of the traffic signals is by the use of thermionic vacuum tubes and oscillating currents of electric energy, the desired control being effected by the change of oscillation of the currents.

In carrying out the invention, advantage is taken of the change of plate current to a tube when the electric oscillation changes in energy as a vehicle or metallic mass passes a part of the circuit carrying the oscillating currents.

A control between the vehicle and the traffic signals is thus obtained by proximity of the vehicle to a device along the highway.

In the accompanying drawing which illustrates the invention,

Figure 1 is a diagrammatic view showing a thermionic tube with its source of energy and its electric circuits together with a pair of wheels representing a vehicle or moving metallic mass.

Figure 2 shows a main highway and cross street with its traffic signals, in this case light signals together with a part of the electric circuits carrying electric oscillations placed in the roadway of the cross street on either side of the main highway.

The operation of the device is as follows:

Referring to Figure 1:

A thermionic vacuum tube 4 has its filament 5 heated from a source, in the case 115-volt, 60-cycle, through a lamp 6 as a resistance.

Across filament 5 is a resistance 7 adjustable to give proper filament current.

Across filament 5 is also a resistance 8 with a center tap 9 to give a convenient return for the grid circuit of the tube. The grid 10 connects through grid leak 11 and condenser C₁ to a tuning coil 12 and its condenser C₂ and then to

center tap 9. The plate 13 connects through choke 14 and relay 1 to the line side of lamp 6. The plate also connects to its tuning coil 3 and its condenser C₃ by a by-pass condenser C₅.

With the two coils 12 and 3 tuned to the same frequency, the tube 4 will cause oscillating currents to flow in the tuned coils 12 and 3. To assist this effect a condenser C₄ connects grid 10 to plate 13.

As the circuit currents are oscillating, the plate current through relay 1 is less in amount than when the currents of the tuned coils 12 and 3 are not oscillating.

The tuned coils 12 and 3 can be used at maximum oscillating value normally, and at less than maximum value when coil 3 for example is thrown less in tune by a passing vehicle 2 or the tuned coils 12 and 3 can be used at minimum oscillating value normally and at more than minimum value when coil 3 is thrown into better tuning by a passing vehicle 2.

In the diagram shown with vehicle 2 over coil 3 which is embedded in the roadway, the tuned coils 12 and 3 are at a high value of oscillating current and the relay 1 is at open circuit due to lowering of plate 13 current.

The contacts 4 and 5 of relay 1 are closed causing signal lights G₂ and R₂ to indicate by current from, in this case, a battery 14. G₂ and R₂ control signals to stop for main highway and to clear for cross street.

As vehicle 2 moves away from coil 3, current in coil 3 falls in value, plate 13 resumes normal high value of current through relay 1 causing relay 1 to open contacts 4 and 5 and close contacts 4 and 6 giving current to signal lamps G₁ and R₁, to indicate resumption of clear for main highway and stop for cross street.

This construction of applicants has the feature that the control of the resonant circuit, which results in the control of the signal, is by varying the magnetic induction which is brought about by the passage of the metallic mass on the vehicle and is effective independently of any static induction and therefore provides a means for operating the devices buried in the roadway, notwithstanding the burying of the device shields it from effect by the static induction occasioned by passing persons or other bodies than the metallic mass on a vehicle which is capable of changing the magnetic induction as distinguished from the static induction. The device is only operated therefore, as intended, by passing vehicles and is prevented from false operation by passing pedestrians, animals and the like.

What we claim is:

The combination with intersecting roadways, of a traffic controlling signal at the intersection of said roadways, and means for controlling the 5 signal in accordance with the proximity of a vehicle, comprising a thermionic vacuum tube controlling said signal in accordance with its oscillatory character, a plurality of resonant circuits connected therewith whereby the oscillatory 10 character of said tube may be varied, one of said circuits including an inductance coil beneath the

surface of the roadway and adapted to have its inductance varied by variation in its magnetic induction by the passage of a vehicle carrying a metallic mass in proximity thereto, thereby varying the resonant condition of the last mentioned 80 circuit and consequently varying the oscillatory character of the tube, and means for operatively relating said tube to said signal.
